UNITED STATES PATENT OFFICE.

KARL HEINEMANN, OF BERLIN, GERMANY, ASSIGNOR TO DEUTSCHE WAFFEN- UNI
MUNITIONSFABRIKEN, OF BERLIN, GERMANY.

AUTOMATIC GUN.

1,114,611.

Specification of Letters Patent.

Patented Oct. 20, 1914.

Application filed February 8, 1912. Serial No. 676,283.

To all whom it may concern:

Be it known that I, KARL HEINEMANN, a citizen of the German Empire, residing at Berlin, in the Kingdom of Prussia, Germany, have invented certain new and useful Improvements in Automatic Guns; and I do hereby declare the following to be a full, clear, and exact description of the invention, such as will enable others skilled in the art 10 to which it appertains to make and use the same.

My invention relates to improvements in automatic guns, and more particularly in automatic guns of the Maxim type in which 15 the lock or breech block is moved in opening and closing position by means of a lock lever secured to the right hand end of the lock crank and outside the casing inclosing the breech mechanism. As is known in the art 20 the said lock crank is mounted on a slide block which is reciprocated by the recoil of the barrel, and in such reciprocation the lock lever alternately strikes with its opposite ends on a stationary part in the form 25 of a roller, whereby the said lever and the crank shaft are alternately rocked in opposite directions, and such rocking movement is used for operating the lock.

One of the objects of my improvements 30 is to construct the lock operating mechanism in such a way, that the shocks which are caused by the lock lever striking against the roller are as far as possible avoided.

With this object in view my invention 35 consists in arranging the cams of the lock crank which control the opening movement of the lock inside the breech casing and in position for engagement with a stop bearing on the handle block. Outside the breech casing exclusively the rocking lock lever is located, and the position of rest and the breech closing position of the latter are such, that any pressure and shocks which might occur always act in the direction of the longitudinal axis of the barrel, so that they can 45 not impair the accuracy of aiming of the gun. Preferably the said lock lever is equipped with a buffer spring which dampens the shocks.

50 In order that my invention be more clearly understood an example embodying the same has been shown in the accompanying drawings in which the same letters of reference have been used in all the views to 55 indicate corresponding parts.

In said drawings Figure 1, is a longitudinal section of the breech casing showing the lock mechanism in the closed breech position. Fig. 2, is a similar section showing the operating mechanism for the lock in the open breech position, Fig. 3, is a side view of the breech of the gun showing the lock lever and, in dotted lines, the mechanism for operating the lock, the parts being shown in the closed breech position, Fig. 4, is a similar side view showing the parts in the open breech position, and Fig. 5, is a detail plan view showing the novel parts of the breech mechanism and illustrating the arrangement of the cams controlling the opening movement of the lock relatively to their stops.

Referring to the example illustrated in the drawings, to the handle block *w* provided at the rear of the breech casing a bracket *d* is secured which is provided at its front end with upper stops *c* and a lower rounded stop *e* both of which are located near the longitudinal axis of the barrel. At its rear end the bracket *d* is made in the form of a sleeve *d'* which is provided with internal screw threads and receives a flanged tubular stud *m*. Within the latter the rear extension *n'* of a block *n* is guided which at its front face is formed with a cam face *z* and a roller *y*. Between the flanged portion of the stud *m* and the block *n* a coiled spring *o* is interposed which has the tendency to force the block *n* forward and into the position shown in Fig. 1. 90

In front of the stops *c* and *e* the lock crank shaft is located which has received the reference letter *f*. The crank shaft is reciprocated in the usual way by the recoil of the gun. At its outer end it carries a 95 rocking lever *g* which is weighted at its outer end in the usual way and which assists in imparting to the crank shaft the rocking movement which is necessary for moving the lock into opening and closing position. 100 In guns of the construction now in use stops are provided which act directly on cam faces formed on the rocking lever.

An important feature of my invention 105 consists in arranging the said cam faces separately of the rocking lever and inside the breech casing and near the longitudinal axis of the gun. In the example shown the said cam faces are formed on the lock crank *b* which is made integral with the shaft *f*. 110

As shown the said crank is formed with upwardly projecting fingers *a* having cam faces *a'*. Furthermore the crank is provided with a cam *x* arranged for engagement with stop *y* preferably in the form of a roller and located at the lower end of the block *n*. The crank arms *b* are in the usual way jointed to connecting rods *b'* by means of which the crank is coupled to the side levers of the lock. 5 The operation of the parts so far described is as follows: If the breech mechanism is in the closed position shown in Fig. 1, and the gun is fired, the crank shaft *f* and the parts connected therewith are forced rearward by 10 the recoil. Thereby the fingers *a* engage the stops *c* with their upper ends, so that the crank is rocked downward and the toggle links *b*, *b'* are opened. Upon further movement of the crank toward the left the cam 15 faces *a'* ride on the stops *e* and simultaneously the cam *x* on the roller *y*. Thereby the toggle links are further opened and the lock moved into the open breech position, while the block *n* is forced backward and its spring 20 *o* is compressed. Finally the parts assume the position shown in Fig. 2 in which the breech is open.

The rocking lever *g* secured to the outer end of the crank shaft *f* takes part in the 25 rocking movement so far described and it receives thereby an accelerated rocking movement, so that it is brought from the position shown in Fig. 3 into the position shown in Fig. 4. In the closed breech position the said lever bears on a stop *h* secured to the side wall of the breech casing, and in the open breech position it strikes with a toe *g'* against a stop *i* formed on the slide carrying the crank shaft *f* from which it 30 bounds in the usual way. In order to dampen the shock caused by the impact of the lever *g* when striking on the stop *i* the said lever is provided with a buffer spring *k* which strikes against the stop *i* before the 35 toe *g'* engages the same. As shown the stops *k* and *i* are so arranged relatively to the toe *g'* and the side face of the lever *g*, that the latter strikes against the same in a direction parallel to the longitudinal axis of the gun, 40 so that the accuracy of aiming the gun is not impaired by the shocks caused by the impact of the rocking lever. In the closed breech position the lever *g* is directed vertically downward, and in the open breech position 45 it is directed upward.

I claim herein as my invention:

1. In an automatic gun, a lock crank, a reciprocating slide carrying said crank, means operated by the recoil of the gun to impart 50 reciprocating movement to said slide and its crank, a finger formed on said crank and having a cam face, stops located one in the path of the end of said finger and one in the path of said cam face and adapted in combination with said finger and cam face to im-

part rocking movement to said crank, and means for returning said crank, after being rocked, to its initial position.

2. In an automatic gun, a lock crank formed with an abutment and with a cam face, toggle links connected with said lock crank, a slide carrying said crank, means controlled by the recoil of the gun to impart reciprocating movement to said slide and its crank, stops respectively located in the paths 70 of said abutment and cam face, said abutment and its stop being so located as to open the toggle links, and said cam face and its stop being so located and shaped as to continue the opening movement of the toggle 75 links and to impart an accelerated movement to the crank upon the movement of said slide by the recoil, and means for returning said cam, after being rocked, to its initial position. 80

3. In an automatic gun, a lock crank formed with an abutment and with a cam face, toggle links connected with said lock crank, a slide carrying said crank, means controlled by the recoil of the gun to impart 90 reciprocating movement to said slide and its crank, stops respectively located in the paths of said abutment and cam face, said abutment and its stop being so located as to open the toggle links, and said cam face and its 95 stop being so located and shaped as to continue the opening movement of the toggle links and to impart an accelerated movement to the crank upon the movement of said slide by the recoil, a rebounding member connected with said crank, and a stop co-operating with said rebounding member and adapted to return said crank into initial position. 100

4. In an automatic gun of the Maxim type 105 having a slideable breech block, the combination of the recoil spring, the handle crank shaft, the handle thereon, the reciprocating toggle link device consisting of two toggle links one mounted on the handle crank shaft 110 the other pivotally connected with the slideable breech block, a stop device placed inside the breech casing and adapted to begin the bending of the toggle links, a cam device likewise arranged inside the breech casing 115 and adapted to complete the bending of the said toggle links under the recoil of the gun against the action of the recoil spring, said recoil spring acting against the cam device of the toggle links in order to straighten the latter in co-operation with the handle of the 120 crank shaft.

5. In an automatic gun of the Maxim type, the combination of the reciprocating toggle link device, the handle crank shaft, 125 a stop device inside the breech casing and consisting of a curved projection attached to the toggle link device, a stop and a curved stop both rigidly attached to the breech casing and adapted to co-operate with the pro- 130

jection in order to cause the beginning of
the bending of the toggle link device on the
recoil of the gun, a cam attached to the tog-
gle link device, a counter cam coöperating
with the said first named cam in order to
5 complete the bending of the toggle link de-
vice, a sliding carrier for supporting said
counter cam, a recoil spring acting upon the

said carrier and a weighted handle on the
crank shaft.

10

In testimony whereof I hereunto affix my
signature in the presence of two witnesses.
